CANE MILL

Philip V. Tippet, Ansonia, Conn., assignor to Farrel-Birmingham Company, Incorporated, Ansonia, Conn., a corporation of Connecticut

Application March 7, 1947, Serial No. 732,967

10 Claims. (Cl. 308—22)

1

This invention relates to cane mills, and more particularly to three-roller mills such as commonly used in sugar-cane grinding installations. In such mills there is a cane roll or feeding roll, a top roll, and a bagasse roll.

The present invention has to do primarily with the provisions whereby the side rolls, that is to say, the cane roll and the bagasse roll, are held in the housings. Conditions arise where it is necessary to remove one or both side rolls on short notice, as where a piece of tramp iron has become lodged in the mill, and to install a new roll. Owing to the rapid deterioration of the cane after cutting, it is highly important that such changes or shifts be accomplished with maximum rapidity.

One of the objects of the present invention is to provide a side-roll mounting that will meet these conditions.

Another object is to provide a cane mill having a hinged side cap so constructed and arranged that the removal of the roll and the replacement thereof by a new roll can be accomplished with maximum convenience as well as speed, the amount of manual labor required in connection with the replacement of a roll being decreased to a marked extent, and it being unnecessary for the workmen to lift or carry heavy parts of the assemblage.

Another object is to provide a structure of this kind in which a side cap, hinged at the lower part, can be quickly released and swung downward for the removal of the roll, and the roll then shifted to a position in which it can be lifted by a crane, after which a new roll can be installed in an equally convenient and rapid manner.

In the accompanying drawings:

Fig. 1 is a side elevation of a cane mill embodying my improvements, showing the rolls in their working positions;

Fig. 2 is an enlarged edge view looking from the right of Fig. 1, showing one of the housings, certain parts being shown in section and other parts broken away;

Fig. 3 is a section on line 3—3 of Fig. 2;

Fig. 4 is an enlarged section on line 4—4 of Fig. 1;

Fig. 5 is a partial side elevation showing the side cap of Figs. 2 and 3 in the lowered position, with the roll in a position to be lifted out of the mill;

Fig. 6 is a section on line 6—6 of Fig. 5;

Fig. 7 is a section on line 7—7 of Fig. 5;

Fig. 7A is a section on line 7A—7A of Fig. 5; and

2

Fig. 8 is an inner face view of the cap member.

The present improvements are shown in connection with a three-roller sugar-cane mill having a pair of housings in which are mounted in the usual triangular arrangement a cane roll, a top roll, and a bagasse roll. The first and the third of these rolls, which are known as side rolls, are illustrated as having mountings embodying the present improvements. In each case there is a side cap pivoted at its lower part to the housing, and having means adjacent its upper part whereby it can be locked or fastened to the housing in the operative position so as to hold the side box in position within the housing recess, the arrangement being such that, when the upper end of the cap is released from the housing, the cap can be swung downwardly to a substantially horizontal position, after which the side box can be moved laterally out of the housing recess to a position in which the roll can be lifted out of the mill by a suitable crane, the end of the roll being supported in the meantime upon the side cap, and the side cap in turn being supported from the mill structure in the manner hereinafter described. In the case illustrated the two side caps are of identical structure, and therefore a description of one of them will suffice, and it will be noted that in this particular case the roll mounting which is illustrated in detail is that of the bagasse roll shown at the right of Fig. 1. The mounting is shown in detail in connection with only one of the housings, but it will be understood that an identical structure can be used in connection with the other housing.

In the drawings, the necks of the cane roll, top roll and bagasse roll are indicated respectively at 10, 11 and 12, these being supported within a housing 13 having lower recesses 14 and 15 for the side rolls. In a typical construction used for mounting the bagasse roll, the roll neck is received in a side box 16 which is movable laterally in the recess 15, and is held in adjusted position by means including a side cap 17. This side cap, as above mentioned, is pivoted or hinged at its lower part to the housing, as indicated at 18, and is provided adjacent its upper end with means whereby the upper end can be fastened or locked to the housing in a releasable manner, as hereinafter described. When the upper end of the side cap is released, the side cap can swing down by gravity to the position shown in Fig. 5, and can be supported in that position from the girder bed which extends laterally from the housing base, and when

the cap is in this position the side box can be slid laterally onto the cap, so as to be in a position such that the roll can be lifted out of the mill.

The side box can be adjusted in the housing recess 15 by an adjusting screw 19 having a mounting in the cap, and the cap is also provided with a hold-back bolt 20, and these members can be of any preferred kind. The means for fastening the upper end of the cap to the housing comprises an eye bolt 21 slidably related to the upper end portion of the cap and having an eye adapted to be engaged by a fastening pin 22 slidable in a bore of the housing. The pivot means provided at the lower end of the cap, indicated at 18, comprises a pin passing through the lower extremity of the cap and through housing lugs between which said extremity is inserted. The girder bed which supports the cap when the latter is in the lowered position is indicated at 23.

Referring now to the details, the recess 15, which receives the side box and the roll neck supported therein, has a mouth portion which is opened by the lowering of the side cap to the position of Fig. 5, and the lower part of the recess is defined by a horizontal surface 24 engaging the bottom 25 of the side box, the side box being provided with flanges 26 which guide it as it is moved along the bottom of the housing recess, said flanges being extended over the face surfaces of the housing. The side box is provided with the usual bearing material for mounting the roll neck, and it is provided with the usual boss 27 against which the adjusting screw 19 impinges.

The housing 13 is in the form of a casting, cored out for lightness, and having lugs 28 which project so as to lie alongside opposite side faces of the cap, and these lugs receive the pivot pin 18, and when the lower part of the cap has been thrust between these lugs and the pivot pin 18 inserted through the registering bores, a set screw 29 in a socket of the cap is engaged with a groove 30 in the pivot pin or hinge pin so as to complete the assembly at the hinge of the cap.

The cap member 17 is made in the form of an elongated body of substantially the same width as the housing adapted to extend over and enclose the notch-like bearing space that is provided in the housing. At its inner part the cap body preferably has the formation shown in the drawings, the body having a flat inner face that is adapted to abut at its lower part a vertical face 31 provided upon the housing in a region immediately below the side box recess. This flat face, as shown in Fig. 3, extends upwardly almost to the top of the side box recess to a line indicated at 32, and from this line the cap body is recessed so as to provide an upper end portion 33 of reduced thickness adapted to abut the housing portion that defines the upper part of the side box recess or notch. It is through this reduced portion 33 of the cap body that the eye bolt 21 passes. The eye bolt has a shank portion 34 that extends through a bore 35 provided in the cap body, and the inner end of the shank portion 34 has the eye 36 formed thereon. The shank portion 34 has at the opposite end a threaded portion 37 upon which is a nut 38 adapted to screw up against the outer face of the cap body so as to draw the upper end of the cap body firmly against the housing.

It will be noted from Fig. 3 that the housing, in that portion adjacent the upper part of the side box recess, is extended so as to provide an abutment against which the upper recessed end

of the cap body will seat, said abutment having a generally rectangular opening 39 leading to its outer face, in which the eye 36 is received. In the assembled position the abutment, which is indicated at 40, is disposed within the recess formed by reducing the thickness of the cap body, which recess lies above the line 32 previously mentioned, and is indicated in the drawings at 41. The abutment 40 has upper, lower and side walls surrounding the opening 39, and the upper part of the abutment has a setback to receive a lip 42 provided upon the inner face of the body or block at its upper extremity. From the line 32 the inner face of the block is sloped, as shown at 43, to a line where the flat bottom of recess 41 is reached, and there is thus provided a construction in which, when the block is swung upwardly from the position of Fig. 5 toward the position of Fig. 3, the block will not meet interference but will, on the other hand, be tightly cammed into place against the lower part of the abutment 40. When this occurs, the lip 42 fits closely into the recess or setback in the upper part of the abutment.

The eye 36 of the eye bolt is preferably of generally elliptical shape, the same having a round hole to receive the round locking pin 22, and the sides of the eye being flattened as shown, so as to lie in close proximity to the side walls of the abutment. By this arrangement the eye bolt, when entered into the opening or hole 39, is prevented from turning, which facilitates the insertion of the locking pin 22. It will also be noted from Fig. 3 that, when the eye bolt is entered into the housing abutment, the eye portion of the bolt by resting upon the floor portion of the abutment will be positioned at the correct level for receiving the locking pin. Between the eye proper and the shank portion 34, a portion 34a of intermediate thickness is provided on the bolt, and this portion provides a shoulder that is adapted to abut the cap body for the purpose of limiting the movement of the eye bolt in the bore 35.

The girder bed 23 in this present embodiment is bolted to the mill housing, and is of cored-out structure and has an upper portion that will receive the adjusting screw and the lower portion of the eye bolt when the cap is lowered to the position of Fig. 5. For this purpose the girder bed has a top wall 44 provided with a longitudinal opening 45 that under normal conditions is closed by a plate 46. This plate may be removed before the cap is lowered so as to permit the adjusting screw and the eye bolt to extend down into the girder bed, as shown in Fig. 5, when the cap is in a horizontal position. When the cap is in such position it may be supported in a suitable manner from beneath as by a bar 47 laid across the upper part of the girder bed (Fig. 5). It will be noted that when the cap is horizontal, its inner face is in line with the floor of the recess in the housing, and this permits the side box to be slid laterally to a position in which it rests on the cap. In this position the roll is clear of the housing and can be removed from the mill by a straight lift.

When it is necessary to remove one of the side rolls from the mill, a man places a box wrench on the nut 38, and uses a sledge to loosen the nut about one turn. When this operation is taking place the eye bolt is held against turning by the provisions previously described. On releasing the nut in this manner, the pressure on the eye-bolt pin 22 is relieved, and the pin can be moved to the releasing position shown in Fig.

6 by inserting a pinch bar under its head or in some other suitable manner. The pin does not have to be entirely removed from the housing for the purpose of releasing the eye bolt, and this is an advantage in that there are no loose pieces to be handled. The next step is to attach a sling from an overhead crane to the upper part of the cap, the attachment being effected by suitable projecting members on the cap such as the headed projections 48. The adjusting screw 19 is screwed back in the cap so that its nose does not project beyond the flat inner surface. The hold-back bolt 20 is removed from the cap, this being such a light piece that it can be readily handled by the attendant. The cover plate 46, which is also a light piece, is taken off of the top of the girder bed. All is then ready for lowering the cap to the position shown in Fig. 5, the holding bar or block 47 being used in the manner previously described.

It is believed that the operations incident to the substitution of a new roll will be clear from the previous description. In this operation the cap acts as a table upon which the adjacent roll bearing is received preliminary to being slid into position in the housing. In this movement the side box is effectively guided, inasmuch as the depending side flanges on the side box co-act with the side faces of the cap. These side faces are spaced from each other at substantially the same distance as are the side faces of the housing adjacent the floor of the side box recess.

It will be apparent that the described construction considerably expedites the replacement of side rolls, which is a matter of great importance for the reasons previously noted. Another advantage arises from the convenience with which the necessary operations can be performed by the workmen. The workmen are not required to lift and move heavy and massive parts that are characteristic of sugar mill construction. The construction described is not only one in which the cap when lowered forms a table on the same level as the housing jaw defining the lower boundary of the side recess, but is one in which the mill housing in the general sense of the term is adapted to support the cap very effectively in the lowered position, notwithstanding the great weight placed upon it. It is entirely unnecessary to construct with lumber or otherwise an improvised support for the roll.

It will be noted that when the cap is in the lowered position, the shouldered portion 34 under the eye of the eye bolt rests against the upper or inner surface of the cap, in the manner shown in Fig. 5. The eye bolt associated with the cap provides, in connection with its locking pin and the associated housing parts, a fastening assembly of great efficacy, as well as a structure that is very readily demountable. The eye bolt is mounted in the cap so that the bolt has a limited sliding movement transversely of the cap, and the eye bolt is permanently associated with the cap in the sense that it is not necessary to remove it from the cap when the latter is shifted to the roll-supporting position. This is obviously a great advantage from the standpoint of convenient operation, and also from the standpoint that in sugar-mill practice the reduction of the number of separate or loose parts is highly desirable. As the cap is lowered to the roll-supporting position, the outer or lower end of the eye bolt moves into a recess in the bed without requiring special attention.

Only one embodiment of the invention is shown herein, but it is understood that various modifications and changes may be made without departing from the principles of the invention or the scope of the claims.

What I claim is:

1. In a cane mill, the combination of a housing having a laterally facing open-mouthed recess leading to a side edge of the housing, a cap hinged to the housing below said recess and swingable on its hinge to close said recess and having its upper end abutted against the housing above the recess, and means providing a detachable fastening between the upper end of said cap and the housing, the housing having provision for supporting said cap when the latter is swung downwardly, said recess having a floor portion for supporting a bearing box, and said cap having a portion which when the cap is in the lowered position serves as a continuation of said floor portion onto which the bearing box can be moved.
2. In a cane mill, the combination of a housing having a laterally facing open-mouthed recess leading to a side edge of the housing, a cap hinged to the housing below said recess and swingable on its hinge to close said recess and having its upper end abutted against the housing above the recess, and means providing a detachable fastening between the upper end of said cap and the housing, the housing having provision for supporting said cap when the latter is swung downwardly, said recess having a floor portion for supporting a bearing box, and said cap having a portion which when the cap is in the lowered position serves as a continuation of said floor portion onto which the bearing box can be moved, said means providing a detachable fastening including an eye bolt carried by the cap.
3. In a cane mill, the combination of a housing having a laterally facing open-mouthed recess leading to a side edge of the housing, a cap hinged to the housing below said recess and swingable on its hinge to close said recess and having its upper end abutted against the housing above the recess, and means providing a detachable fastening between the upper end of said cap and the housing, the housing having provision for supporting said cap when the latter is swung downwardly, said recess having a floor portion for supporting a bearing box, and said cap having a portion which when the cap is in the lowered position serves as a continuation of said floor portion onto which the bearing box can be moved, said means providing a detachable fastening including an eye bolt carried by the cap, said eye bolt being mounted in the body of the cap so that it can have a limited sliding movement.
4. In a cane mill, a housing having a bearing-receiving recess leading laterally inwardly from one side edge, a cap hinged at one end to the housing below the recess and adapted to be swung upwardly to close the recess, and means including an eye bolt carried by the cap adjacent its free end for connecting the free end of the cap to the housing, said eye bolt being received and held in a transverse bore provided in the cap between the ends of the cap.
5. In a cane mill, a housing having a bearing-receiving recess leading laterally inwardly from one side edge, a cap hinged at one end to the housing below the recess and adapted to be swung upwardly to close the recess, and means includ-

ing an eye bolt carried by the cap adjacent its free end for connecting the free end of the cap to the housing; said eye bolt being received and held in a transverse bore extending through the cap between the ends of the cap and arranged to have a limited sliding movement in said bore when the upper end of the cap is released from the housing.

6. In a device such as described, a notched housing and a cap hinged at one end for closing the notch in the housing, the free end portion of the cap carrying an inwardly projecting eye bolt received in a socket provided in the housing, and a locking pin insertable into the eye of the eye bolt for securing the cap in assembled position, said eye bolt having a shank disposed and held in a bore through the cap between the ends of the cap, the shank being provided with threads at the outer side of the cap and having a tightening nut engaging said threads and said shank, having at the inner side of the cap a shoulder adapted to engage the cap when the latter is swung downwardly to a certain extent.

7. In a device such as described, a housing having a bearing-receiving notch leading to a side edge thereof, and a cap hinged to the housing adjacent the lower end of the cap and having an upper free end adapted to be fastened detachably to the housing with the cap in bridging relation to the notch, the housing being provided with a bed portion adapted to support the cap while the latter is in a lowered substantially horizontal position, the cap having an adjusting screw extending therethrough to engage the bearing and the bed portion being formed to clear the adjusting screw when the cap is in the lowered position.

8. In a device such as described, a housing having a bearing-receiving notch leading to a side edge thereof, and a cap hinged to the housing adjacent the lower end of the cap and having an upper free end adapted to be fastened detachably to the housing with the cap in bridging relation to the notch, the housing being provided with a bed portion adapted to support the cap while the latter is in a lowered substantially horizontal position, the cap having an adjusting

5 screw extended through it and also having near its free end an externally projecting fastening bolt for the cap, the housing bed being formed to receive parts of the adjusting screw and the fastening bolt when the cap is in the lowered position.

9. In a device such as described, a housing having a lateral notch leading inwardly from one side edge, a hinged cap for closing said notch, the hinge of the cap being located adjacent the lower part of the notch, the lower part of the notch providing a floor for a side box and the cap when lowered providing a continuation of said floor, and a side box having a base and guide means associated with the base for guiding it along said floor and said continuation.

10. A cane mill having a housing provided with a bearing-receiving notch leading to a side edge thereof, a cap for bridging said notch hinged to the housing adjacent the lower end of the cap and having an upper free end adapted to be fastened detachably to the housing, said cap having an endwise adjustable member extending therethrough and projecting from the outer face of the cap, and a bed portion on said housing adapted to support the cap from beneath while the latter is in a lowered substantially horizontal position, said bed portion being formed to clear said adjustable member when the cap is in the lowered position.
